HOUSING FOR A CARPET SWEEPER

Robert G. Plantholt, Drayton Plains, Mich., assignor to
Bissell, Inc., Grand Rapids, Mich., a corporation of
Michigan

Application October 1, 1959, Serial No. 57,745

Term of patent 14 years

(Cl. D9—2)

Fig. 1 is a front perspective view.

Fig. 2 is an end elevational view.

Fig. 3 is a plan view of a housing for a carpet sweeper embodying my design.

This application is a continuation-in-part of my prior copending application Serial No. 51,744, filed July 11, 1958.

I claim:

The ornamental design for a housing for a carpet sweeper, as shown.
